(57) **ABSTRACT**

A new and distinct *Salvia* plant of unknown parentage is provided that was discovered in a nursery setting while growing among other *Salvia* plants. Over a long blooming season in abundance attractive bicolored blossoms are formed having a pink and salmon coloration. The growth habit is compact and bushy. Attractive large green leaves are formed. Following pruning, the plant displays a tendency to vigorously regrow. The plant is well suited for providing attractive ornamentation.

2 Drawing Sheets

1

Botanical/commercial classification: *Salvia hybrida*/
Salvia Plant.
Varietal denomination: Cv. Fancy Dancer.

SUMMARY OF THE INVENTION

The new *Salvia* cultivar of the present invention was discovered while growing in a plant nursery setting among other *Salvia* plants at Watsonville, Calif., U.S.A. The new cultivar is of unknown parentage and likely includes *Salvia microphylla* in its ancestry. The new plant was distinguished from other *Salvia* plants growing in the nursery where it was discovered primarily through a study of its distinctive bicolored blossoms of pink and salmon coloration combined with other attractive botanical characteristics identified hereafter. Had the single plant of the present invention not been discovered and carefully preserved, it would have been lost to mankind.

The plant is a perennial that can be grown to advantage without protection in U.S.D.A. Hardiness Zone Nos. 7 to 11.

It was found that the new *Salvia* cultivar possesses the following combination of characteristics:

- (a) displays a compact and bushy growth habit,
- (b) forms in abundance over a long blooming season attractive bicolored blossoms having a pink and salmon coloration,
- (c) forms attractive large green leaves,
- (d) displays a tendency to vigorously regrow following pruning, and
- (e) is well suited for providing attractive ornamentation.

The new cultivar of the present invention can be readily distinguished from other *Salvia* cultivars, such as the 'Shell Dancer' cultivar (U.S. Plant Pat. No. 20,680). More specifically, the new variety is considerably more compact and includes a slightly brighter pink coloration.

2

The new cultivar well meets the needs of the horticultural industry and can be grown to advantage as attractive ornamentation in parks, gardens, public areas, and residential landscapes.

5 The new cultivar has been asexually reproduced by the rooting of cuttings for several generations. Such asexual reproduction as performed at Watsonville, Calif., U.S.A., and near West Grove, Pa., U.S.A., has demonstrated that the characteristics of the new cultivar are firmly fixed and stable and are strictly transmissible from one generation to another. Accordingly, the new cultivar asexually reproduces in a true-to-type manner from one generation to another.

The new cultivar has been named 'Fancy Dancer'.

15 BRIEF DESCRIPTION OF THE PHOTOGRAPHS

The accompanying photographs show the new variety as nearly true as it is reasonably possible to make the same, in color illustrations of this character. The photographs were obtained on Apr. 17, 2012 near West Grove, Pa., U.S.A., and illustrate a typical container grown plant and plant parts of the new variety.

20 FIG. 1 illustrates the overall compact growth habit of a flowering plant of the new variety.

25 FIG. 2 illustrates a closer view of the foliage and the bicolored pink and salmon blossoms of the new variety.

DETAILED DESCRIPTION

30 The chart used in the identification of colors is that of The Royal Horticultural Society (R.H.S. Colour Chart) of London, England (1995). Color terminology in common terms sometimes is included as an aid to the reader. Such color terminology is to be accorded its customary dictionary significance. The description is based on the observation of typical specimens of the new variety at an age of approxi-

mately one year during April 2012 while growing indoors in containers under natural light at West Grove, Pa., U.S.A.

Plant:

<i>Form</i> .—Bushy, vigorous, and compact.	5	<i>Calyx upper lobe width</i> .—Commonly approximately 8 mm in width.															
<i>Height</i> .—Commonly approximately 51 cm on average.	5	<i>Calyx lower lobe number</i> .—2.															
<i>Width</i> .—Commonly approximately 53 cm on average.		<i>Calyx lower lobe shape</i> .—Acute.															
<i>Growth habit</i> .—Perennial in U.S.D.A. Hardiness Zone Nos. 7 to 11.		<i>Calyx lower lobe length</i> .—Commonly approximately 1.4 cm on average.															
<i>Leaf arrangement</i> .—Opposite.	10	<i>Calyx lower lobe width</i> .—Commonly approximately 7 mm on average.															
<i>Leaf configuration</i> .—Elliptic to oblong.		<i>Corolla shape</i> .—Tubular proximally to two-lipped distally.															
<i>Leaf length</i> .—Commonly approximately 4.3 cm on average.		<i>Corolla length</i> .—Commonly approximately 1 cm on average.															
<i>Leaf width</i> .—Commonly approximately 2 cm on average.	15	<i>Corolla color</i> .—The base commonly is White Group 155C, the tube is near Red-Purple Group 63D overlaid with Red-Purple Group 63B, and the lower lip is Red-Purple Group 63B on the upper lobes of the lower lip, and Red Group 56C on the lower lobes of the lower lip.															
<i>Leaf margin</i> .—Repand.		<i>Corolla tube length</i> .—Approximately 13 mm on average.															
<i>Leaf texture</i> .—Commonly slightly fleshy.		<i>Corolla tube depth</i> .—Approximately 7 mm on average.															
<i>Leaf blade color</i> .—Green Group 137A on the upper surface, and Green Group 138B on the under surface.		<i>Corolla tube lip number</i> .—3.															
<i>Leaf blade apex</i> .—Acute to obtusely rounded.	20	<i>Corolla upper lip number</i> .—1.															
<i>Leaf blade base</i> .—Mainly obtuse.		<i>Corolla upper lip shape</i> .—Hood-like.															
<i>Scent</i> .—Leaves commonly display a tangy fruity scent when crushed.		<i>Corolla upper lip length</i> .—Commonly approximately 11 mm average.															
<i>Petiole shape</i> .—Somewhat flattened.		<i>Corolla lower lip length</i> .—2, suborbicular.															
<i>Petiole length</i> .—Variable and commonly approximately 1.9 cm.	25	<i>Corolla lower lip shape</i> .—Banner-like, and extended downward.															
<i>Petiole width</i> .—Commonly approximately 1 mm.		<i>Corolla lower lip outline</i> .—Obovate.															
<i>Petiole color</i> .—Green Group 143C.		<i>Corolla lower lip length</i> .—Commonly approximately 15 mm on average.															
Inflorescence:		<i>Corolla lower lip diameter at tip</i> .—Approximately 16 mm on average.															
<i>Time</i> .—Prolonged blooming period beginning in May and extending through September near West Grove, Pa., U.S.A.	30	<i>Style length</i> .—Approximately 2 cm on average.															
<i>Type</i> .—Terminal raceme.		<i>Style width</i> .—Commonly less than 1 mm on average.															
<i>Diameter</i> .—Commonly approximately 4.5 cm on average.	35	<i>Style attachment site</i> .—At four-lobed ovary between lobes.															
<i>Length</i> .—Commonly approximately 29 cm on average.		<i>Ovary</i> .—Approximately 2 mm in length, approximately 1 mm in diameter, and near Yellow-Green Group 145A in coloration.															
<i>Number</i> .—Commonly up to approximately 46 flowers per plant on average in bloom at a given time.		<i>Stamen number</i> .—1.															
<i>Configuration</i> .—Tubular, and two-lipped.	40	<i>Stamen shape</i> .—Seesaw-like.															
<i>Pedicel length</i> .—Commonly approximately 5 mm on average.		<i>Filament length</i> .—Approximately 8 mm on average.															
<i>Pedicel width</i> .—Commonly approximately 1 mm on average.		<i>Connective length</i> .—Approximately 6 mm on average.															
<i>Pedicel color</i> .—Green, Green Group 143D overlaid with Greyed-Purple Group 183A.	45	<i>Anther length</i> .—Approximately 2 mm on average.															
<i>Pedicel pubescence</i> .—None observed.		<i>Anther diameter</i> .—Less than 1 mm on average.															
<i>Calyx shape</i> .—Broadly campanulate and flared towards the apex.		<i>Anther color</i> .—Greyed-Orange Group 163C.															
<i>Calyx rib number</i> .—Commonly 14 and longitudinally disposed.	50	<i>Anther attachment site</i> .—At outer end of the connective.															
<i>Calyx length</i> .—Commonly approximately 1.5 cm on average.		<i>Pollen</i> .—Abundant.															
<i>Calyx width</i> .—Commonly up to 1.1 cm.		<i>Development</i> :															
<i>Calyx texture</i> .—Glandular and puberulent on the upper and under surfaces.	55	<i>Vegetation</i> .—Vigorous and displays a tendency to quickly regrow following pruning.	<i>Calyx color</i> .—On the upper lobe Green Group 143C overlaid with Greyed-Purple Group 183A towards the apex, and on the lower lobes Green Group 141D overlaid with Greyed-Purple Group 183A towards the apex.	60	<i>Blooming</i> .—Displays long blooming season.	<i>Calyx lobe number</i> .—3.		<i>Fertility</i> .—Not observed with the plants being sterile during observations to date.	<i>Calyx upper lobe number</i> .—1.		<i>Winter hardiness</i> .—The plant is a perennial that can be grown in at least U.S.D.A. Hardiness Zone Nos. 7 to 11.	<i>Calyx upper lobe shape</i> .—Acute.		<i>Disease resistance</i> .—No particular sensitivity to disease has been encountered during observations to date.	<i>Calyx upper lobe length</i> .—Commonly approximately 1.5 cm on average.	65	
<i>Vegetation</i> .—Vigorous and displays a tendency to quickly regrow following pruning.																	
<i>Calyx color</i> .—On the upper lobe Green Group 143C overlaid with Greyed-Purple Group 183A towards the apex, and on the lower lobes Green Group 141D overlaid with Greyed-Purple Group 183A towards the apex.	60	<i>Blooming</i> .—Displays long blooming season.	<i>Calyx lobe number</i> .—3.		<i>Fertility</i> .—Not observed with the plants being sterile during observations to date.	<i>Calyx upper lobe number</i> .—1.		<i>Winter hardiness</i> .—The plant is a perennial that can be grown in at least U.S.D.A. Hardiness Zone Nos. 7 to 11.	<i>Calyx upper lobe shape</i> .—Acute.		<i>Disease resistance</i> .—No particular sensitivity to disease has been encountered during observations to date.	<i>Calyx upper lobe length</i> .—Commonly approximately 1.5 cm on average.	65				
<i>Blooming</i> .—Displays long blooming season.																	
<i>Calyx lobe number</i> .—3.		<i>Fertility</i> .—Not observed with the plants being sterile during observations to date.	<i>Calyx upper lobe number</i> .—1.		<i>Winter hardiness</i> .—The plant is a perennial that can be grown in at least U.S.D.A. Hardiness Zone Nos. 7 to 11.	<i>Calyx upper lobe shape</i> .—Acute.		<i>Disease resistance</i> .—No particular sensitivity to disease has been encountered during observations to date.	<i>Calyx upper lobe length</i> .—Commonly approximately 1.5 cm on average.	65							
<i>Fertility</i> .—Not observed with the plants being sterile during observations to date.																	
<i>Calyx upper lobe number</i> .—1.		<i>Winter hardiness</i> .—The plant is a perennial that can be grown in at least U.S.D.A. Hardiness Zone Nos. 7 to 11.	<i>Calyx upper lobe shape</i> .—Acute.		<i>Disease resistance</i> .—No particular sensitivity to disease has been encountered during observations to date.	<i>Calyx upper lobe length</i> .—Commonly approximately 1.5 cm on average.	65										
<i>Winter hardiness</i> .—The plant is a perennial that can be grown in at least U.S.D.A. Hardiness Zone Nos. 7 to 11.																	
<i>Calyx upper lobe shape</i> .—Acute.		<i>Disease resistance</i> .—No particular sensitivity to disease has been encountered during observations to date.	<i>Calyx upper lobe length</i> .—Commonly approximately 1.5 cm on average.	65													
<i>Disease resistance</i> .—No particular sensitivity to disease has been encountered during observations to date.																	
<i>Calyx upper lobe length</i> .—Commonly approximately 1.5 cm on average.	65																

I claim:

1. A new and distinct *Salvia* plant characterized by the following combination of characteristics:
  - (a) displays a compact and bushy growth habit,

US PP24,088 P3

5

(b) forms in abundance over a long blooming season attractive bicolored blossoms having a pink and salmon coloration,
(c) forms attractive large green leaves,

5

6

(d) displays a tendency to vigorously regrow following pruning, and
(e) is well suited for providing attractive ornamentation; substantially as illustrated and described.
